CLAIM

The ornamental design for a flashlight, as shown and described.

DESCRIPTION

FIG. 1 is a front and top perspective view of a flashlight, showing my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is an enlarged perspective view of detail "8" identified in FIG. 1; and,

FIG. 9 is an enlarged rear elevation view of detail "9" identified in FIG. 5.

The dashed broken lines in the drawings illustrate portions of the article and form no part of the claimed design. The dash-dot-dash broken lines in FIGS. 1, 5, 8, and 9 are for the purpose of depicting the enlarged views and form no part of the claimed design.
